UNITED STATES PATENT OFFICE.

GEORGE R. LAIDLAW, OF MARION, INDIANA, ASSIGNOR OF TWO-FIFTHS
TO LEE STEVENS, OF SAME PLACE.

DEVICE FOR CONVERTING MOTION.

SPECIFICATION forming part of Letters Patent No. 605,553, dated June 14, 1898.

Application filed October 20, 1897. Serial No. 655,795. (No model.)

To all whom it may concern:

Be it known that I, GEORGE R. LAIDLAW, a citizen of the United States, residing at Marion, in the county of Grant and State of Indiana, have invented a new and useful Device 5 for Converting Motion, of which the following is a specification.

This invention relates to a new and useful improvement in devices for converting motion; and it consists in the construction and 10 arrangement of parts hereinafter described, and definitely pointed out in the claims.

The aim and purpose of this invention is to construct a device whereby a reciprocating motion can be changed to a rotary motion. 15 This invention further contemplates the construction of a device that not only converts the reciprocating motion to a rotary motion, but at the same time largely increases the 20 power of the rotary motion.

A further object is to so construct the device that the direction of the rotary motion can be reversed independently of the direction of the reciprocating motion—that is to 25 say, that the reciprocating motion is always in one direction and that the rotary motion is reversed independently of the reciprocating motion.

A still further object is to construct a device 30 which can be operated by a small amount of power, easily controlled, and cheaply manufactured.

These and other objects not hereinbefore mentioned are accomplished by the construction 35 illustrated in the accompanying drawings, wherein like letters of reference indicate corresponding parts in the several views, and in which—

Figure 1 is a side elevation of my improved 40 device. Fig. 2 is a vertical section on the line *a a*, Fig. 1. Fig. 3 is a section on the line *b b*, Fig. 4; and Fig. 4 is a detail view of the clutch-shoe.

In the drawings, *A* designates a pulley, which 45 is supported on the axle or support *D*. The pulley *A* can be either rigidly or loosely supported on the axle, as desired. If supported rigidly on the axle, the axle will turn and the power will be taken from the axle. If loosely 50 supported on the axle, the power can be taken

direct from the pulley by means of a belt, which it is not deemed necessary to show.

The pulley is provided with a hub *A'*, on which are loosely journaled two arms or levers *B C*. The arm or lever *B* is longer than 55 the arm or lever *C* and is adapted to be connected, as shown at *P*, directly with the reciprocating motive power. This reciprocating motive power is not shown, as it is evident that any suitable source of power can 60 be used. The upper end of the arm or lever *C* has pivoted to it a connecting-rod *O*. The opposite end of this rod is pivoted to a rock-arm *L*. This rock-arm is pivoted to the framework, as shown at *M*, and has its opposite end 65 pivoted to the connecting-rod *N*, which is pivoted to the lever *B* at *N'*, all as shown in Fig. 1. It will thus be seen that the lever *C* is moved by the lever *B*, and by referring to the arrows, Fig. 1, it will be seen that the movement of the lever *C* is at all times directly opposite the movement of the lever *B*. 70

Pivotedly secured to the lower ends of the levers *B C* are the clutch-shoes *E*, as clearly shown in Fig. 2. Each lever is provided with 75 two such shoes, and the shoes of each lever extend in opposite directions, as shown in Fig. 1, and normally will rest and bear against the inner surface of the pulley *A*. The bearing-faces of the clutch-shoes *E* are provided 80 with the portions *F*, as shown in Fig. 4, which can be made of compressed paper or other suitable frictionable material. The portions *F* are secured to the shoe by means of bolts *F'*. The shoes are provided with the upwardly-extending flanges *E'*, which are provided with the apertures *E''*, through which a bolt *E'''* passes to pivotally secure the shoes 85 to the levers. As will be seen by referring to Fig. 1, the shoes are only secured to the levers at one end, so that the free ends of the shoes will normally bear against the pulley. 90

H designates shifting rods which are slidingly secured in the boxes *I*, which are supported by the pieces *R* of the supporting frame. There are two of these rods; one on each side of the pulley, as shown in Fig. 2. *J* designates a reversing-lever which is pivoted and fulcrumed on the standard *R'* on the frame. The lower end of the reversing-lever 100

is pivoted to the cross-piece K, connecting the shifting rods by means of the elongated slot K, so that when the lever is moved the rods are either moved to the right or left. 5 Rigidly secured to the rods H are the shifting or reversing links G. The free ends of the shoes E are secured to the links by means of the pins Q' on the shoes. The pins are provided with the antifriction-roller Q'. The 10 slot in the links are so shaped that the pins Q can describe the necessary arc of a circle when it is desired that the shoe will bear against the pulley, and the links are so positioned on the rod H that when one shoe is 15 in operative position the oppositely-arranged shoe on each lever will be held from contact with the pulley, and therefore not in operative position.

By referring to Fig. 1 it will be seen that 20 the links are so positioned that the right-hand shoe is in operative position and that the left-hand shoe is not. The right-hand shoe on the opposite side of the pulley is also in operative position, while the left-hand shoes are 25 both out of position. Now when motion is imparted to the lever B the lever C will move in the opposite direction, as before described. When the lever B is moving in the direction of the arrow, Fig. 1, the right-hand shoe will 30 bear against the inner surface of the pulley and rotate the pulley in the direction of the arrow. When the lever has reached the limit of its movement and moves in the opposite direction, then the lever C, carrying the 35 shoe on the opposite side of the pulley, will exert power and continue to rotate the pulley, while the shoe pivoted to the lever B is loosely sliding over the inner surface of the pulley to its initial position. It will thus be seen 40 that when the levers are being actuated the shoes are continually bearing against the pulley, rotating the same, and that the power is alternately exerted on opposite sides of the pulley.

45 When it is desired to change the direction of the pulley, the lever J is reversed, sliding the shifting rods H to the left and bringing the left-hand shoes into operative position and lifting the right-hand shoes out of contact with the inner surface of the pulley. It 50 will thus be seen that the movement of the pulley can be readily reversed by simply reversing the lever J, and that it is not necessary to reverse the movement of the reciprocating motive power. When it is desired to disconnect the pulley from the reciprocating power, the lever J is brought to an upright vertical position, thereby disconnecting all 55 of the shoes from the pulley and allowing the pulley to rotate independently of the levers, so that the levers can continue to be in motion and the pulley at a standstill or moving at a greater or less speed. By this arrangement it makes the device especially desirable 60 65 and useful for hoisting purposes where it is desirable to drop the load quickly and without stopping the engine. It will also be read-

ily noticed that it is adaptable to a great variety of uses where it is necessary to reverse the motion or disconnect the driving power 70 from the motive power.

By pivoting the shoes at only one end to the levers the free ends will have a tendency at all times to bear against the inner surface of the pulley, and by providing the curved links 75 engaging the free ends of the shoes the links will act as a guide and increase the frictional contact as well as disengage the shoes when slid over.

It will be noticed by referring to Fig. 4 that 80 the shoe is provided with a detachable bearing-surface and that this detachable portion gradually increases in width toward its free end for the reason that the friction is greater there than at any other point. 85

I am aware that many minor changes can be made in the construction and arrangement of parts without in the least departing from the nature and principles of my invention.

Having thus described my invention, what 90 I claim as new, and desire to secure by Letters Patent, is—

1. In a device for converting motion, the combination with a pulley, of a lever rotatably secured on the hub of the pulley, oppositely-extending clutch-shoes having one of their ends pivoted to the lever and their free ends adapted to bear against the inner surface of the pulley and adapted to rotate the pulley when the lever is moved in one direction and have a sliding contact with the pulley when the lever is moved in the opposite direction, and means for disengaging one of the shoes or both of the shoes from operative contact with the surface of the pulley. 105

2. In a device for converting motion, the combination with a pulley, of a pair of reciprocating levers, oppositely-extending clutch-shoes having one end pivotally secured to each lever and adapted to engage the inner surface 110 of the pulley, and means for disengaging all of the shoes or one of the shoes of each lever from operative contact with the inner surface of the pulley.

3. In a device for converting motion, the combination with a rotatable pulley, of a pair of reciprocating levers, oppositely-extending clutch-shoes pivotally secured to each lever and adapted to engage the pulley, and shifting rods engaging the shoes to disengage all 120 of the shoes or one of the shoes of each lever from operative contact with the pulley.

4. In a device for converting motion, the combination with a rotatable pulley, of a pair of reciprocating levers, oppositely-extending clutch-shoes pivotally secured to the levers and adapted to engage the inner surface of the pulley, shifting rods slidably secured, and curved links engaging each shoe for disengaging them from operative contact with 130 the pulley.

5. In a device for converting motion, the combination with a rotatable pulley, of a pair of reciprocating levers, oppositely-extending

clutch-shoes having one end pivotally secured to the levers and adapted to engage the inner surface of the pulley and on opposite sides of the inner surface thereof, and means for disengaging the corresponding shoe of each lever from operative contact with the surface of the pulley.

6. In a device for converting motion, the combination with a rotatable pulley, of a pair of reciprocating levers, oppositely-extending clutch-shoes adapted to engage the inner surface of the pulley and having one end pivotally secured to the levers, a projection on the

opposite ends of the shoes, sliding shifting rods, curved links secured to the rod and 15 adapted to engage the projections on the shoes adapted to guide the shoes into operative contact with the pulley or disengage them from the pulley.

In testimony whereof I affix my signature in presence of two witnesses.

GEORGE R. LAIDLAW.
